UNITED STATES PATENT OFFICE.

HENRY A. MINER, OF MALDEN, MASSACHUSETTS.

DESIGN FOR A BOTTLE-CAP.

40,386.

Specification for Design.

Patented Dec. 7, 1909.

Application filed March 15, 1909. Serial No. 483,657. Term of patent 3½ years.

To all whom it may concern:

Be it known that I, HENRY A. MINER, a citizen of the United States, residing at Malden, in the county of Middlesex and State of Massachusetts, have invented a new, original, and ornamental Design for a Bottle-Cap, of which the following description, in connection with the accompanying drawings, is a specification, like numerals on the drawings representing like parts.

In the accompanying drawings, I have shown a perspective view of the bottle cap, in which there is a downwardly and out-

wardly flaring neck 1 terminating at its upper edge in a bead 2 above which is a dome shaped fluted portion having vertical convex ribs 3 all coming together at the center of the top at 4.

I claim—

The ornamental design for a bottle cap, as shown and described.

HENRY A. MINER.
